Primary Examiner — Clare E Heflin(74) *Attorney, Agent, or Firm* — Gardner Groff Greenwald & Villanueva, PC(57) **CLAIM**

The ornamental design for a lighting fixture, substantially as shown and described.

DESCRIPTION

FIG. 1 is a perspective view of a lighting fixture according to the design.

FIG. 2 is a first side view of the lighting fixture of FIG. 1.

FIG. 3 is a second side view of the lighting fixture of FIG. 1.

FIG. 4 is a front view of the lighting fixture of FIG. 1.

FIG. 5 is a rear view of the lighting fixture of FIG. 1.

FIG. 6 is a top view of the lighting fixture of FIG. 1; and,

FIG. 7 is a bottom view of the lighting fixture of FIG. 1.

Portions shown in broken lines are for illustrative purposes only and form no part of the claimed design.
